FLIER

Michael C. McDermott, Cleveland, Ohio, assignor
to Industrial Rayon Corporation, Cleveland,
Ohio, a corporation of Delaware

Application March 16, 1949, Serial No. 81,802

6 Claims. (Cl. 57—116)

1

This invention relates to fliers. More particularly this invention relates to fliers of the type used in textile twisting and spinning machines.

In the twisting of yarns of heavier denier it is desirable to restrict a flier in rotation during certain periods to substantially the rotation of a supply spool to prevent yarn and the like from over-running the spool when the spool is decelerated or stopped. The over-running of yarn usually causes "corkscrews" and a backing up 10 of twist to the point of departure of the yarn on the spool. Then, before the twisting machine is restarted the "corkscrews" have to be eliminated; and where a great many spools are attended by an operator a considerable time is taken in readjusting the yarn. Sometimes the "corkscrews" are carried through the flier onto a collecting spool occasionally breaking the flier; and should the imperfect portion pass through the flier eye the collected yarn is defective and it will create further difficulties in later processing steps. Also, a "corkscrew" may back up to the surface of the spool and the twisted yarn may become ensnared with the laid turns on the spool to damage the yarn.

Various types of fliers have been devised having braking means to restrict the independent rotation of the flier at spool starting and stopping periods. Such braking means may comprise air paddles to act as air brakes; centrifugally releasable braking devices that are adapted to hold and release a projection positioned in the flier body; a resilient friction brake such as a spring type brake that is responsive to certain speeds and which acts on the top of a spool to frictionally bind the flier to the spool; and expanding springs which frictionally restrain the rotation of the flier yet permit a relative rotation between the flier and the spool. The mentioned braking devices generally have been found not sufficient in the control of yarn upon deceleration so as to be adaptable in the spinning of heavier denier yarns. This invention, advantageously provides a flier for use with such yarns. The flier has an integrated braking device in addition to an air-brake which operates to restrict the rotation of the flier to that of the spool at starting or stopping periods. Further, the flier is advantageously provided with a combination air-brake and air-lift device which is adapted to disengage the braking means and allow the flier to rotate independently of the spool.

Generally, the flier comprises a mounting adapted to be placed about a spindle protruding above a spool of yarn, a sleeve about this mounting, and a sleeve about the latter sleeve carrying the guide eye of the flier and the air-brake lift. The inner sleeve has a flared, conical, section and the surrounding sleeve, being adapted to

2

rotate relative to the inner sleeve, also has a conforming flared section. When at rest, or substantially so, the outer sleeve rests on the flared section of the inner sleeve. During rotation, however, the air-brake lift acts to raise the flier off the flared section of the inner sleeve.

The advantages of the flier will be more thoroughly explained in the following description and in the accompanying drawing where:

Figure 1 represents in elevation the flier of this invention;

Figure 2 is an isometric view of the flier; and

Figures 3, 4, 5 and 6 are sectional views of the flier taken along lines 4—4, 5—5 and 6—6 respectively.

Referring to the drawing, a thread 10 is withdrawn from a supply spool 11 through a flier 13 positioned about a spindle 12 supporting the spool 11. The thread is led through the flier eye 20 and from thence to a further forwarding or collecting device. The flier 13 generally comprises a body portion 15 having at one end an air-lift brake 16 and at the opposite end an arm 17 containing the flier eye 20.

In the body portion of the flier, as shown in Figure 2, there is positioned the flier supporting sleeve 21 which is adapted to rotate about an inner sleeve 22 also having within it a further pressure fitted sleeve 25 which is adapted to be frictionally positioned about the spindle 12. The flier body 15 is provided with an aperture through which extends the flier supporting sleeve 21. The flier body 15 is positioned about the sleeve 21 in a press fitting manner and it is held securely thereto by a locking washer or ring 26. Thus secured the sleeve 21 is adapted to rotate with the flier body 15. The sleeves 25 and 22 fit snugly together and both are adapted to rotate with the spool spindle 12.

As shown in Figures 3 and 4 the sleeve 22 has an outwardly flared conically shaped bottom portion 24 and the lower portion of the flier supporting sleeve 21 has a complementary outwardly flared section 29. When the sleeve 21 is raised free of the flared section 24 it is then adapted to rotate relative to the sleeve 22 and independently of the spool 11; however, when the sleeve 21 drops, as by gravity, into frictional contact with the flared portion 24 it becomes bound thereto to rotate at substantially the same speed as the sleeve 22 and the spool 11.

About the cylindrical portion 23 of the sleeve 22 there is provided a vertical limit stop such as collar 27 for the flier body. The collar 27 is fitted about the sleeve 23 and it is retained in position by a locking device 28; both the collar 27 and the locking device 28 are positioned in grooves provided for them in the sleeve 22. The innermost sleeve 25 extends outwardly of the sleeve 22 at both ends and it is crimped there-

over so as to become securely fastened therewith.

In order to raise the flier from its position of rest the supporting sleeve 21 is raised off the flared section 24 by the air brake and lift 16 which is advantageously angularly positioned to the direction of travel as shown in Figure 5. The air brake 16 functions as a propeller and its angular resistance to the air causes the flier to rise. Where the supply spool 11, in a twisting operation, is adapted to rotate at speeds of around 5,000 R. P. M. and over the propeller action of the flier air brake 16 along with the lifting action of the upwardly drawn yarn substantially immediately raises the flier off the friction binding section 24. The flier is then adapted to freely rotate about the spindle 12 relative to the spool 11 to continually readjust itself to the various yarn withdrawing and twisting conditions. The angularly positioned flier brake 16 also substantially compensates for the lifting action of the withdrawn yarn when it is pulled through the eye 26.

Where it is deemed that the raising action of the flier air brake 16 is not effective soon enough upon starting a twisting operation then the lift of the flier can be further increased by tapering the body portion 16 to the direction of its rotation. When the flier body 15 is formed with reinforcing ribs or side braces, such as the ribs 30, 31 shown in Figure 6, the ribs are desirably angularly positioned to the direction of their rotation. Such an angular positioning of the forward and rearward reinforcing braces 30, 31 of the flier, on one side of the central support or on both sides along with an angularly positioned air-brake, will more quickly raise the flier from its position of rest on the tapered section 24.

I claim:

1. A flier being adapted for positioning about a spindle, said flier comprising; a body portion having an aperture, a support for mounting said flier about the spindle in said aperture, a brake in said support, a yarn guiding eye positioned on one side of said flier body, an air paddle on the other side of said flier body, said air paddle being inclined to the direction of rotation and to a plane through the axis about which it rotates, and said inclined air paddle upon rotation being adapted to vertically raise the flier and render the brake inoperative.

2. A flier adapted for positioning about a spindle, a body portion having an aperture, a support for said flier in said aperture adapted to be positioned about a spindle, a brake in said support, an air paddle on one side of said body portion, a yarn guiding eye on the opposite side of said body portion, said air paddle and body portion both being inclined to the direction of rotation and to a plane through the axis about which it rotates, and said inclined air paddle and body portion being adapted upon rotation to vertically raise the flier and to render the brake inoperative.

3. A flier comprising, a body portion having an aperture, a supporting sleeve secured in said aperture of said body portion, an inner sleeve within said supporting sleeve being adapted to be positioned about a spindle, a flared portion on said inner sleeve on which said flier supporting sleeve is adapted to rest, a yarn guiding eye on one end of said body portion through which thread or the like is adapted to pass, and an air paddle on the other end of said flier body being inclined to the direction of rotation and to a plane through the axis about which it rotates, and said inclined air paddle being adapted upon

rotation to vertically raise said flier supporting sleeve from the flared portion of said inner sleeve.

4. A flier comprising, a body portion having an aperture, a supporting sleeve secured in said aperture of said body portion, an inner sleeve within said supporting sleeve, said inner sleeve being adapted to be positioned about a spindle to rotate therewith, said inner sleeve having a flared portion and said supporting sleeve having a seat portion complementary to said flared portion so that said supporting sleeve is adapted to rest on said flared portion, said complementary seat and flared portions forming a brake, a thread guiding eye attached to said body portion, an air paddle attached to said body portion opposite said guiding eye, and said air paddle being inclined to the direction of rotation and to a plane through the axis about which it rotates, and said inclined air paddle being adapted upon rotation to vertically raise said flier supporting sleeve from said flared portion.

5. A flier comprising, a body portion having a centrally positioned aperture, a supporting sleeve positioned in said aperture being secured to said body portion, an inner sleeve within said supporting sleeve being independent of said supporting sleeve, said inner sleeve being adapted to be positioned about a spindle to rotate therewith, said inner sleeve having a flared portion and said supporting sleeve having a seat portion complementary to the flared portion the supporting sleeve being adapted to rest on the flared portion of the inner sleeve, said complementary seat and flared portions forming a brake for said flier, a thread guiding eye attached at one end of said body portion, an air paddle attached to the body portion opposite said guiding eye, and said air paddle being inclined to the direction of rotation and to a plane through the axis about which it rotates, and said inclined air paddle being adapted upon rotation to vertically raise said flier to render the brake inoperative.

6. A flier comprising, a body portion having a centrally positioned aperture, an air paddle on one end of said body portion being inclined to the direction of rotation and to a plane through the axis about which it rotates, a thread guiding eye attached to the body portion opposite said air paddle, said body portion being inclined on either side of said aperture to the direction of rotation to effect a lifting of said flier, a supporting sleeve secured in said aperture of said body portion, an inner sleeve within said supporting sleeve, and said inner sleeve having a flared portion and said supporting sleeve having a seat portion complementary to the flared portion, the supporting sleeve being adapted to rest on said flared portion and to be braked thereby.
